COMPRESSOR.

Application filed March 1, 1923. Serial No. 622,023.

The invention relates to gas compressors and particularly to the type used in small refrigerating machines of the compression type.

Home refrigerating devices are, in general, cumbersome and complicated, and require a comparatively large compressor unit. The compressors are usually motor driven and have a relatively low speed as compared with that of the motor, requiring the use of reduction gears, which increase the friction factor in the device as well as render it noisy. The use of a motor of high starting torque is necessary to overcome the inertia of the pistons when starting the compressor. The cost of this type of motor is about double that of the ordinary induction type, and its life is shorter. Also, a motor having the necessary horsepower to operate a refrigerating machine with this type of compressor, has a current consumption out of proportion to the capacity of the machine.

An object of the invention is to provide a high speed compressor adapted for direct connection to a motor, and embodying valves operable at a speed hitherto found impracticable.

Another object of the invention is to provide a high speed compressor having a low friction factor, requiring a relatively low horsepower electric motor for operation and so constructed that the need for a motor with a high starting torque is eliminated.

Another object of the invention is to provide a compressor with the lubricating oil under the discharge pressure of the compressor, so that the lubrication is positive and continuous.

Another object of the invention is to provide a small compressor as an integral part of a refrigerating unit, that may be doubled or quadrupled in capacity without increasing the size of the unit, thus increasing the rating of the refrigerating unit in the same proportion.

The invention possesses other objects and features of advantage, some of which, with the foregoing, will be set forth in the following description of our invention. It is to be understood that we do not limit ourselves to the showing made by the said description, as we may adopt variant forms of our invention within the scope of the claims.

Referring to the drawings: Fig. 1 is a perspective view of the refrigerating unit installed on a refrigerator. A portion of a side wall and the back of the refrigerator are broken away in order to show the complete unit. Fig. 2 is a perspective view of the compressor on its flanged mounting with the cover plate removed. Fig. 3 is a horizontal cross section thru the compressor on the lines 3—3, Fig. 2. The cover plate for the compressor is shown in addition. Fig. 4 is an elevation of the eccentric block showing the oil passages. Fig. 5 is a view of one of the exterior friction faces of the eccentric block, showing the oil grooves therein. Fig. 6 is a plan view of the valve. Fig. 7 is a perspective view of the compressor with the cylinder block and base plate partially pulled away from the flange mounting, showing the slot in the gasket, leading from the suction port to the main shaft. Fig. 8 is a vertical cross-section thru the compressor on the line 8—8, Fig. 2. The compressor is shown mounted in the discharge chamber of the apparatus. Fig. 9 is a diagrammatic section thru the cylinder block of the compressor in its preferred form with four cylinders. Fig. 10 is a plan view of the cylinder block shown in Fig. 9. Fig. 11 is a diagrammatic section thru the cylinder block of the compressor showing a modified arrangement giving eight cylinders and doubling the capacity of the compressor. Fig. 12 is a plan view of the cylinder block shown in Fig. 11. Fig. 13 is a plan view of two cylinder blocks similar to the one shown in Fig. 9, placed together, showing another modified form having eight cylinders. Fig. 14 is a plan view of two cylinder blocks, similar to the one shown in Fig. 11, placed together, showing a modified form giving sixteen cylinders and quadrupling the capacity of the compressor. Fig. 15 is a diagrammatic section thru a modified form of cylinder block showing an arrangement having eight cylinders. Fig. 16 is a plan view of the cylinder block shown in Fig. 15. Fig. 17 is a diagrammatic section thru the cylinder block on the line 17—17, Fig. 16, showing the position of the eccentrics. Fig. 18 is a plan view of two cylinder blocks, similar to the one shown in Fig. 15, placed together, showing another modified form having sixteen cylinders.

Broadly stated, our invention comprises a compact gas compressor of the piston type mounted in and discharging into a closed casing or receiver, adapted to hold a quantity of lubricating oil. Passages are provided so that this oil under receiver pressure may flow to the various bearings. The compressor embodies suction and discharge valves of rapid and certain action, and with positive and continuous lubrication the high speed incident to direct connection to a motor becomes possible.

The compressor designated as a whole by the character 1 is directly driven by a motor 2 and is mounted on a cover plate 3, forming the closing head of a casing or receiver 4, enclosing the chamber 6, into which the compressor discharges. Both receiver and motor are mounted upon a base 7. The compressed gas passes from the discharge chamber 6, thru the pipe 8 into the condenser 9 where the heat developed by the compression and condensation is absorbed by a stream of water, in the coils 11, entering the bottom of the condenser. The water passes from the condenser coils thru the pipe 12, which is preferably wrapped around the casing 4 in the coils 13. From the condenser the liquid sulphur dioxide is conducted thru the pipe 14 to the expansion valve 16 in the compartment 17, which is to be cooled and which forms the upper part of the refrigerator 18. There it is expanded into the coils 19, 20, and 21, which have a cooling surface sufficiently large to chill the compartment. The expanded gas is then conducted back to the compressor thru the pipe 22 to begin a new cycle.

The compressor, in its preferred form, comprises a cylinder block 23, preferably in the form of a square ring, with a base plate 24 on one side, and a cover plate 26, on the opposite side. The three are secured together and to the receiver cover plate 3, by suitable screws 27 and studs 28. The space within the square ring forms the compressor supply chamber 29 into which the expanded gas discharges from the passage 31, which extends from the pipe 22 thru the receiver cover plate 3, and base plate 24, to terminate in an inlet port in one corner of the supply chamber.

Formed in the peripheral walls of the cylinder block are bores comprising four cylinders 33, 34, 36 and 37, radially disposed at 90° intervals about the axis of the drive shaft 38. Integrally formed on the drive shaft is an eccentric 39, with shoulders 40 and 41, Fig. 3, adapted for engagement with the interior surfaces of the cover plate 26 and the base plate 24, respectively, thereby keeping the eccentric centered in the inlet chamber. Revolvably mounted about the eccentric is an eccentric block 42 having exterior surfaces disposed at 90° to each other.

Adapted for vertical movement, but rigidly fixed against horizontal movement, is a piston rod or bar 43, adjacent the face 44 of the eccentric block, with interior horizontal faces 46 and 47 adapted for engagement with the exterior faces 48 and 49, respectively, of the eccentric block. Seated loosely in suitable recesses formed in the piston rod and secured thereto by screws 51, are two oppositely disposed vertical pistons 52 and 53, adapted to work in cylinders 33 and 34, respectively. Similarly, a piston rod 54, adjacent face 56 of the eccentric block 42, is adapted for horizontal movement, but is rigidly fixed against vertical movement. This piston rod has interior vertical faces 57 and 58 adapted for engagement with faces 59 and 61, respectively, of the eccentric block. Attached to the piston rod 54 by screws 62, are two oppositely disposed horizontal pistons 63 and 64 adapted to work in cylinders 36 and 37, respectively. Slot 66 in the piston rod 43 and slot 67 in the piston rod 54, allow a vertical and a horizontal movement respectively of each piston rod with reference to the drive shaft.

Rotating the shaft causes a circular movement of the eccentric block about the axis of the shaft, the exterior friction faces of the block maintaining parallelism, due to their respective engagements with the piston rods, which, together with the connected pistons, are given a reciprocating motion. Each piston is a quarter of its complete stroke in advance of the next following one, and each piston completes a full compression and suction stroke on the same single turn of the crank shaft.

Establishing communication between the inlet chamber 29 and each of the cylinders 33, 34, 36 and 37, are the suction ports 68. These suction ports are opened and closed directly by the pistons, communication being established with each cylinder in turn as the piston completes its suction stroke. This insures a full charge of gas in the cylinder for each compressive stroke, the vacuum in the cylinder, as the piston nears the end of its suction stroke, causing a maximum amount of the gas from the inlet chamber, at substantially zero or atmospheric pressure, to be rapidly drawn into the cylinder. Since each cylinder has direct access to the relatively large inlet chamber, which is filled at all times with sulphur dioxide gas at substantially atmospheric pressure, a cushioning action results, thereby eliminating any tendency toward a "wire drawing" effect which would be present if each cylinder obtained its charge, thru separate leads, from a remote source of gas supply.

The end of each cylinder constitutes a discharge port, the bores extending entirely thru the peripheral wall of the cylinder block. The valves 69, seat directly

on the exterior surfaces of the cylinder block over the open end of the bore, and comprise a thin circular plate or disk having a circumference sufficiently greater than that of the cylinder to provide seating surface. The edge of the disk is provided with notches 71 to decrease the bearing area on the seat and therefore lessen any tendency of the valve to stick. The notched edge also allows the compressed gas to pass the valve more rapidly when open. The valve is kept centered over the cylinder by the valve housing 72, rigidly secured to the cylinder block, and has a very slight movement which is limited under normal operating conditions by the stop 74. The valve contacting face of the stop is rounded to allow a greater latitude for movement of the edge of the valve in the event of its sticking. A pin 77, rigidly mounted in the valve housing, extends thru a hole in the stop, of slightly greater diameter than the pin, and a spring 79 presses the stop inwardly to its normal position against the pin. In case the compressor becomes filled with liquid sulphur dioxide or lubricating oil, a straining of the valves by the discharge of the liquid therethru, is prevented by the increased movement of the valve permitted by movement of the stop against its spring.

The compressed gas escapes from the valve housings 72, directly into the chamber 6, thru ports 80, except from the lower valve housing, in which a tube 81 extends from the port and terminates well above the center of the chamber, as shown in Fig. 8. A gauge 82 records the pressure of the gas in the receiver, and the suction pressure is shown on a gauge 83 in communication with the inlet passage 31.

The head of a piston at the completion of the compression stroke is substantially coincident with the lower face of the valve, just enough space being provided between them to eliminate pounding. The valve action is certain under all conditions, the valve being opened by the compressed gas in the cylinder and seated by a back pressure which is but slightly less than that developed in the cylinder. This certain action combined with an extremely small movement, allows the high speed valve action necessary for a compressor directly coupled to an electric motor.

A positive and continuous lubrication is necessary in a compressor operating at the speed contemplated for my device. The discharge chamber 6 contains a quantity of lubricating oil 84, partly submerging the compressor, the try cocks 85, indicating maximum and minimum oil levels in the chamber, which are below the end of the tube 81. From the above it will be clear that the oil is at all times under the dis-

charge pressure of the compressor, and as it absorbs heat therefrom, acts as a cooling medium, any excessive amount of heat absorbed being removed by radiation from the large surface of the housing 4, and by the cooling coil 13. Under the conditions I have described, the oil will remain at a temperature ranging from 90° F. to 120° F., its viscosity between these temperatures varying but slightly. The size of the oil holes and grooves in the compressor, giving the most efficient and economical lubrication, has been worked out, with the average viscosity of lubricating oil between these temperatures, as a basis.

The cover plate 26 is provided with a bearing 87 adapted to receive one end of the drive shaft 38. The outer end of the bearing is tapped to receive an elbow 88 in which is screwed a short length of pipe 89, extending below the surface of the oil. A wick 91 is attached to the inside of the pipe 89 to prevent the oil from entering too rapidly and to strain out any particles of foreign matter. The oil on passing the elbow provides lubrication for the bearing 87 and enters the drive shaft thru a central passage 92 extending to a point midway between the two vertical faces of the eccentric 39. A smaller passage 93 in communication with and at right angles to the passage 92, extends thru the eccentric to its highest point providing means for lubricating the eccentric and the interior circular face of the eccentric block. Oil passages 94, having an angular separation of 90°, extend thru the eccentric block and communicate with oil grooves 96 in the outer or peripheral faces which are in frictional engagement with the piston rods, thus providing lubrication for the piston rods 43 and 54 engaging these faces. At the completion of the compression stroke of each piston, the oil passage 93, Fig. 3, in the eccentric becomes alined with an oil passage 94 in the eccentric block, and these two with the end of the piston, so that oil is forced thru the passages and about the piston under the discharge pressure of the compressor.

The portion of the drive shaft in the bearing 97 of the base plate 24 receives positive lubrication thru an oil passage 98 in the plate, extending radially from the axis of the bearing. The lower portion of this passage is tapped to receive a threaded tube 99, extending below the surface of the oil. Establishing communication between the drive shaft and the inlet passage 31, Fig. 7, is a slot 101 in a gasket 102, interposed between the base plate 24 and the head 3. As the gas in the inlet passage is, in normal operation of the refrigerating device, under substantially zero or atmospheric pressure, and oil in the passage 98 is under the discharge pressure, an oil pressure, equivalent to the

- difference between the suction pressure and discharge pressure, is established in the bearing of the drive shaft. This lubrication of the bearing 97 provides an oil seal for the stuffing box 103, which comprises a gland 104 held against the packing by a spring 106, the tension of which is controlled by the nuts 107 thru the plate 108, which bears on one end of the spring.
- 10 The compressor shown in the drawings has a stroke of $\frac{1}{2}$ -inch and a bore of $\frac{1}{2}$ -inch. As each piston completes one full suction and discharge stroke in one revolution of the drive shaft, the piston 15 travel for one revolution of the shaft is 2 inches. As the shaft is turning over at the rate of about 1750 revolutions per minute, the piston travel in that period is 3500 inches. Previous types of compressors with the same stroke and bore would have a very much lower capacity. For purposes of comparison, consider a two cylinder compressor of $\frac{1}{2}$ -inch stroke and bore and of the type usually incorporated in 20 small refrigerating machines. The piston travel, per revolution of the shaft, is 1 inch. At 350 revolutions per minute, the piston travel is 350 inches, or one-tenth of the piston travel in the preferred form of the compressor shown, indicating but one-tenth of the capacity. In my compressor apparatus, the friction losses have been found to be about 19%, under ordinary operating conditions. Other losses bring the total up to 25 31%, the machine having a theoretical rating of about 108 pounds and an actual rating of about 75 pounds, one pound of refrigeration being equivalent to the absorption of 144 B. t. u.'s per 24 hours. The rating varies with the suction pressure, and at a suction pressure of 0 pounds and a discharge pressure of 40 pounds, is about 75 pounds, while with a suction pressure of one pound and a discharge pressure of 40 30 pounds, the rating is increased about 20%.
- The invention in its preferred form comprises a four-cylinder compressor, as shown diagrammatically in Figs. 9 and 10, but modifications of the same type will give 35 double and quadruple the capacity of the preferred form without increasing the external dimensions of the compressor, the casting enclosing the discharge chamber having been designed to accommodate such modifications.
- Using the same cylinder block, an eight-cylinder compressor may be made by forming, in each side of the cylinder block, a pair of cylinders 113 and 114, as shown in 40 Figs. 11 and 12, each pair of pistons 116 and 117 operating as a unit.
- Another eight-cylinder modification, as shown in Fig. 13, is the combination of two cylinder blocks 118 and 119, of the type 45 shown in Fig. 9, the eccentrics for operating

the four pistons in each block being set 180° apart.

A combination of two cylinder blocks of the eight-cylinder type, as shown in Figs. 11 and 12, makes a sixteen-cylinder compressor, as shown in Fig. 14.

Another modification giving eight cylinders is obtained by making the cylinder block 121, Fig. 16, to accommodate two cylinders 122 and 123 in each side thereof, the axis of the cylinders lying in vertical and horizontal planes passing thru the axis of the drive shaft, as shown in Figs. 15, 16 and 17.

A combination of two cylinder blocks 121, Fig. 18, makes another modified form having 16 cylinders. Four eccentrics are required on the drive shaft.

We claim:

1. In a compressor, a housing enclosing a supply chamber and formed with bores comprising cylinders, pistons arranged in said cylinders, means for reciprocating said pistons, means for introducing the gas to be compressed into said chamber, means for establishing communication between each cylinder and said chamber prior to the beginning of the compression stroke of the piston therein, means for permitting the escape of the compressed gas from the cylinder, a receiver for said compressed gas enclosing said housing and adapted to hold a quantity of oil, and passages extending from below the oil level to said pistons and said reciprocating means.

2. The combination with a fluid compressor mechanism including bearings of a receiver for the compressed fluid and adapted to hold a quantity of oil, and passages extending from below the oil level to said bearings.

3. The combination with a fluid compressor mechanism including a drive shaft, of a receiver for the compressed fluid and adapted to hold a quantity of oil, a passage extending from below the oil level to one side of said shaft, and a passage extending from the other side of said shaft to the intake of said compressor.

4. In a compressor, a housing comprising a square ring and enclosing a supply chamber and formed with cylinder bores extending entirely thru the sides of the ring, pistons arranged in said cylinders, means for reciprocating said pistons, means for introducing the gas to be compressed into said chamber, passages from said chamber and opening into each cylinder adjacent its inner end so as to be uncovered at the end of the suction stroke of the piston therein, and a plate valve comprising an unattached disk overlying the opposite open end of each cylinder.

5. In a compressor, a housing enclosing a supply chamber and formed with cylinder

- bores extending entirely therethru, pistons arranged in said cylinders, means for reciprocating said pistons, means for introducing the gas to be compressed into said chamber, 5 means for establishing communication between one end of each cylinder and said chamber prior to the beginning of the compression stroke of the piston therein, a plate valve overlying the opposite open end of 10 each cylinder, and a spring-pressed stop for limiting the movement of said plate valve.
6. In a compressor, a hollow block enclosing a supply chamber and formed with radially disposed bores in the peripheral walls 15 thereof comprising cylinders, pistons arranged in said cylinders, a shaft, an eccentric disk on said shaft in said chamber, a square block in which said disk is rotatable, a pair of bars connecting radially opposite 20 pistons and in which said block is slidably arranged, said bars lying on opposite sides of said block, means for introducing the gas to be compressed into said chamber, means for opening communication between each 25 cylinder and said chamber prior to the beginning of the compression stroke of the piston therein, and means for permitting the escape of the compressed gas from the cylinder.
- 30 7. In a compressor, a hollow block enclosing a supply chamber and formed with radially disposed bores in the peripheral walls thereof comprising cylinders, pistons arranged in said cylinders, a shaft, an eccentric disk on said shaft in said chamber, a block in which said disk is rotatable, bars connecting radially opposite pistons and in which said block is slidably arranged, means for introducing the gas to be compressed into said chamber, means for opening communication between each cylinder and said chamber prior to the beginning of the compression stroke of the piston therein, means for permitting the escape of the 35 compressed gas from the cylinder, a receiver for said compressed gas enclosing said housing and adapted to hold a quantity of oil, and passages extending from below the oil level to said shaft, disk, block and pistons.
- 40 8. In a compressor apparatus, a receiver adapted to hold a quantity of oil, a cover plate for closing one end of said receiver, a housing enclosing a supply chamber mounted on the inside of said cover plate and 45 formed with bores comprising cylinders, 50 pistons in said cylinders, a shaft extending from said chamber to the outside of said receiver, means for operatively connecting said shaft to said pistons, valves for permitting said pistons to draw fluid from said supply chamber and discharge it into said receiver, and passages extending from one side of said shaft to below the oil level and from the other side of said shaft to said chamber.
- 55 9. In a compressor, a cylinder having a valve seat at the end thereof coextensive with the bore of the cylinder, a valve comprising an unattached disk arranged on said seat, and spring-pressed means for limiting the opening movement of said disk.
- 60 10. In a compressor, a cylinder having a valve seat at the end thereof coextensive with the bore of the cylinder, a valve comprising an unattached disk arranged on said seat, a stop having a rounded head disposed adjacent said disk, means for permitting limited movement of said stop, and a spring for retaining said stop in position closest to 65 said disk.
- 70 11. In a compressor apparatus, a receiver adapted to hold a quantity of oil, an enclosed compressor seated therein and discharging into said receiver, oil grooves in the operating mechanism of said compressor 75 which become alined with each piston at the completion of its compressive stroke and establish communication between the piston and the oil in said receiver.
- 80 12. In a compressor, a casing, a hollow block within said casing and enclosing a supply chamber, said hollow block being formed with a plurality of pairs of alined bores extending through its walls and comprising cylinders, pistons arranged in said 85 cylinders and rigidly connected in pairs, means for reciprocating said pistons, means for introducing fluid to be compressed into said supply chamber, a port connecting each cylinder with the supply chamber and 90 adapted to be uncovered by the piston prior to the beginning of the compression stroke, and means for permitting the escape of the compressed fluid from the outer and open 95 ends of the cylinders to the interior of the 100 casing.
- 105 In testimony whereof, we have hereunto set our hands.

HENRY C. MARCUS.
WILFRED FOURNESS.
